UNITED STATES PATENT OFFICE.

WILLIAM H. SOMERSALL, OF BOSTON, MASSACHUSETTS.

CHICKEN-BROODER.

No. 853,038.

Specification of Letters Patent.

Patented May 7, 1907.

Application filed December 8, 1906. Serial No. 346,979.

To all whom it may concern:

Be it known that I, WILLIAM H. SOMERSALL, of Boston, in the State of Massachusetts, have invented a new and useful Improvement in Chicken-Brooders, of which the following is a specification.

The invention consists in a brooding compartment provided with a ceiling of transparent glass and a hover immediately beneath said ceiling having an open work top and hanging curtains, substantially as herein described.

The invention consists further in details of construction.

In the drawings, Figure 1 is a cross-section partly in elevation of my improved brooder. Fig. 2 is a plan on line 2—2 of Fig. 1. Fig. 3 is a sectional view on an enlarged scale through the hover and heater. Fig. 4 is a plan view of the hover.

A is the chicken house, or a box about 30 inches square and of a height as shown, but the exact proportions are not essential, forming the casing of my improved brooder. A¹, A², A³, A⁴, are the walls of the said box, or chicken house, and A⁵ is cover for the same, suitably hinged at a.

F is the floor formed of smooth matched boards, and G the ceiling of the compartment M in which the chickens are confined and brooded, the said floor F having a hole at the middle through which passes a heater H, presently to be described, the outer wall of a portion of which closely fits said hole in said floor, as shown. The ceiling G of the compartment M is formed of two plates of window glass or other suitably transparent substance hinged to the walls of the compartment and cut away at their adjoining edges, as shown, to permit the passage of pipe D² forming a part of the heating apparatus, as will be described. These transparent plates of the ceiling G are supported by an inner lining a² of the walls of the compartment M, and upon cross-beams B which in turn are supported on a wire frame n forming the top of a hover, V, which will presently be described.

J is a door in one of the walls of compartment M.

F¹ is the floor of compartment M¹ which may be termed the cellar of the chicken house or box, A, being immediately under the brooding compartment M, while F² is the ground or the bottom of the said chicken house or box.

L is a drawer in the middle of wall A⁴ in compartment M¹ about 5 inches wide and of suitable height, there being attached thereto a false floor or thin strip of wood or metal, l, of the same width extending over the floor F¹ beyond the middle of said floor and carrying, as shown, an oil lamp L², of which T is the oil tank, T¹ the throat, T² the burner, and t the lamp wick regulator.

The heater H is made of sheet metal and comprises an outer drum c that extends through an opening in the floor F of the hover compartment, the lower portion c' thereof being of greater diameter than the body and projecting beneath said floor. Said outer drum is closed at its lower end, which is supported by means hereinafter described just above the level of the top of the burner of the lamp, so that the flame from the lamp will extend into the lower chamber of the inner drum. This chamber is connected with the upper chamber D' by a plurality of flues d, the solid portion D of the top of said lower chamber between said flues acting as a baffle to direct the products of combustion into the flues.

D² is a pipe extending from the chamber D' into the compartment M².

O, O', etc., are air holes in the ring chamber c extension to admit to said extension and chamber c' and c from the compartment M¹ fresh air which has entered said compartment M¹ through a finger-hole, P, in drawer L, by means of which the said drawer L and with it the lamp L² are pulled out of or pushed back into operative position, the said air after being heated, as will be described, passing through holes O¹, O', near the top of the ring chamber c into the compartment M just below the ceiling G, or rather into a hover, V, within said compartment, which will presently be described. The smoke or fumes from the flame of the lamp strike against the plate D by which they are deflected so as to enter the pipes d, d, whence they pass into the chamber D' and then through the pipe D² into the compartment M². The air entering the outer drum of the heater through the openings o circulates freely about the flues or pipes d before passing out through the openings o'. It is thus evident that fresh air becomes heated in its passage through the ring chamber c and about the said hot-air pipes, and that it nowhere minglest with the smoke or fumes from the lamp L.

P¹, P¹ are ventilating holes in compartment

ment M² through which the smoke or fumes from pipe D² finally pass into the open air.

The water-tight vessel W having a hole at the middle for the passage of the chimney or pipe D² is partially filled with water through the water gate w and then placed in position at the top of the heater in the depression of the ring chamber c, as shown. The water in the tank W once heated in the manner indicated in the drawings, *i. e.*, by the smoke and fumes in chamber D¹ and pipe D² and the hot air in fresh-air or ring chamber c which was once cold, will retain sufficient heat throughout a night to prevent harm to the chickens, should the lamp go out.

The top of the water-tight vessel overhangs the outer walls of the ring chamber c, as shown, and carries props r, r, extending up to wires n in the top of the hover, which will next be described. This hover, V, consists of an open top frame n, already mentioned, formed of wires, like an umbrella frame, suitably set in a ring n¹ which closely fits over the pipe or chimney D², and rests upon the water-tight vessel W, the said wires extending out just under the transparent ceiling, G, so as to lie above rather more than one-half of the floor space of compartment M, while from a ring n² connecting the outer ends of said wires hang, like a portiere, curtains or strips of felt arranged to break joints, and reaching to or nearly to the floor F. It is obvious that by merely lifting the cover A⁵ of the chicken house, the chicken raiser at any time may see through the transparent ceiling G and the open top of the hover, every part of the floor F, and every chicken on the floor, both those within and those without the hover, without movement of the hover and without affecting the temperature of any part of the compartment in which the chickens are brooded.

The said ring chamber extension c of the heater H spreads out from the ring chamber c beneath the floor F, as shown, and the said heater is held in position in said floor, as shown, by screw-hooks K of L-shape screwed into the floor from below and having their hooks or handles turned beneath chamber extension c¹.

It is evident that this brooder may be readily taken down and the parts packed within a small space for shipping.

I claim,—

55 1. A chicken brooder, having a compartment provided with a suitable floor, a transparent ceiling and a hover having an open top-frame and hanging curtains.

2. A chicken brooder, having a compartment provided with a suitable floor, a transparent ceiling, a hover within said compartment and having an open top-frame and curtains hanging from the outer circumference thereof to the floor of said compartment, and a central heater passing through said hover. 60

3. The herein described chicken brooder comprising three compartments arranged one above another, a hover having an open top and hanging curtains arranged within the middle compartment, a heating apparatus 70 extending through the floor of said middle compartment into the hover, a lamp within the lower compartment adapted to heat said heating apparatus, a movable roof for the upper compartment, and a transparent body 75 forming the floor for said upper compartment and the ceiling of the middle compartment.

4. A chicken brooder, having a compartment containing a hover, a heater comprising an outer drum extending through the 80 floor of said compartment into the hover and having suitable air inlet and discharge openings, an inner drum consisting of lower and upper chambers and a plurality of flues connecting said chambers, a discharge flue 85 extending from the upper chamber of said inner drum through the top of the hover compartment, a lamp arranged to discharge products of combustion into the lower chamber of the inner drum, and a water vessel supported by 90 said drums.

5. A chicken brooder, having a compartment containing a hover, a heater comprising an outer drum extending through the floor of said compartment into the hover, the 95 lower end of said drum being of greater diameter than the portion thereof within the hover and projecting beneath the floor of the hover compartment, said drum having suitable air inlet apertures formed therein beneath the floor of the hover compartment and air discharge outlets formed in its walls within the hover, an inner drum consisting of lower and upper chambers and a plurality of flues connecting said chambers, a discharge 105 flue extending from the upper chamber of the inner drum through the top of the hover compartment, and a lamp arranged to discharge products of combustion into the inner drum, and supports for said drums depending from the floor of the hover compartment. 110
